United States Patent

Des. 238,257

Patented Dec. 30, 1975

238,257

ROTARY REFLECTOR

Richard Rios, 1429 E. Mission,
Escondido, Calif. 92025

Filed Nov. 15, 1974, Ser. No. 524,051

Term of patent 14 years

Int. Cl. D10—06

U.S. Cl. D10—111

FIG. 1 is a perspective view of a rotary reflector, showing my new design.

FIG. 2 is a side elevational view thereof, as taken from the left hand side of FIG. 1.

FIG. 3 is a front elevational view thereof, as taken from the right hand side of FIG. 2.

I claim:

The ornamental design for a rotary reflector, substantially as shown.
